UNITED STATES PATENT OFFICE.

THEODORE JOSEPH PRITCHARD, OF SUNSHINE, LOUISIANA.

GRATE-BAR.

SPECIFICATION forming part of Letters Patent No. 741,546, dated October 13, 1903.

Application filed April 23, 1903. Serial No. 153,991. (No model.)

To all whom it may concern:

Be it known that I, THEODORE JOSEPH PRITCHARD, a citizen of the United States, and a resident of Sunshine, in the parish of Iberville and State of Louisiana, have invented 5 a new and Improved Grate-Bar, of which the following is a full, clear, and exact description.

This invention relates to a hollow grate-bar through which a current of air is passed to accelerate combustion of the fuel. The grate-bar is adapted especially to be used in connection with a bridge-wall and according to the construction here shown is formed of 15 a lower or body section and a mating top section, which latter is raised above the ordinary level of the grate, the top section having shielded orifices therein, through which the draft is passed into the fuel. The bridge-wall is formed with a draft-tunnel, and air-pipes pass from this tunnel into the hollow grate-bars, said bars having adjacent to the bridge-wall two or more openings discharging the air-current directly upon the wall, 25 and thereby acting as twyers to permit supplying oxygen to the gases passing over the bridge-wall.

This specification is an exact description of one example of my invention, while the claims 30 define the actual scope thereof.

Reference is to be had to the accompanying drawings, forming a part of this specification, in which similar characters of reference indicate corresponding parts in all the views.

Figure 1 is a perspective view of the invention. Fig. 2 is a longitudinal section of the grate-bar, and Fig. 3 is a cross-section on the line 3 3 of Fig. 2.

As shown best in Figs. 2 and 3, the bottom 40 or body member *a* is formed in the shape of a trough and has extensions *a'* at its ends, which rest on the bridge-wall and furnace-setting, as shown in Fig. 1. The body member is also formed with transversely-extending 45 bracing-ribs *a''*, having openings at their lower sides to permit the ashes to pass downward to the lower or central portion of the body-section, where such ashes may be withdrawn through an opening *a''*. The top part 50 *b* of the grate-bar is rounded, as shown in Figs. 1 and 2, and is formed with a number of air-escape openings *b'*, covered by shields

b'', which prevent the entry of ashes into the grate-bar. The said sections *a* and *b* of the bar are held together by tie-bolts *c* 55 and *d*, the tie-bolt *c* being located at the end portions of the grate-bar and the tie-bolt *d* being located at the middle, all of said bolts extending vertically and the bolt *d* serving also to hold in place a closure *e*, which covers 60 the opening *a''*. *d'* indicates a key by which the parts *d* and *e* are removably connected.

As shown in Fig. 1, the grate-bar is preferably arranged with one end on the furnace-setting and the other end on the bridge-wall, 65 although I prefer to arrange between each of my improved grate-bars a number of the ordinary grate-bars *f*, which lie in a plane below the top *b*, so that the fuel spread over this composite grate will be best subjected to 70 the action of the air supplied to the furnace. Reference to Figs. 1 and 2 also will show that two of the openings *b'* at the ends of the grate-bars adjacent to the bridge-wall are turned directly toward the bridge-wall, and the shields 75 are also extended in this direction. This causes the draft passing through said openings to extend over the top of the bridge-wall and mingle with the gases of combustion at this point, so as to bring about effective combustion of the fuel. 80

Air is supplied to the interiors of the grate-bars by means of air-pipes *g*, which are engaged with nipples *a''* on the lower or body sections *a* and which pass from said nipples 85 downward and thence rearward through the front of the bridge-wall into the draft-tunnel formed therein, the receiving ends of the air-pipes being flared or funnel-shaped, as indicated at *g'* in Fig. 1. 90

With the parts assembled as in Fig. 1 it is my purpose to supply air to the fire-box through the ash-pit, as usual, and also to permit an additional supply to pass through the pipes *g* into my improved hollow grate-bars. 95 This provides for the best possible supply of oxygen, and consequently for a thorough and economic utilization of the fuel employed. The grate-bar being sectional, as shown, may be readily repaired, since the greatest heat 100 will be on the top section *b*, and if this should become injured it may be removed and a new section applied to the old body, thus bringing about a great saving, as will be apparent.

Various changes in the form, proportions, and minor details of my invention may be resorted to at will without departing from the spirit and scope thereof. Hence I consider myself entitled to all such variations as may lie within the intent of my claims.

Having thus described my invention, I claim as new and desire to secure by Letters Patent—

1. A hollow grate-bar, comprising upper and lower longitudinal sections, each of approximately the length of the bar, the edges of which sections are engaged together to form the grate-bar and the upper section having an air-discharge orifice therein, means for fastening said sections in place, the bottom section having an orifice for the introduction of a current of air into the grate-bar, and a bracing-rib located in the bottom section and extending from side to side thereof.

2. A hollow grate-bar, comprising upper and lower longitudinal sections, each of approximately the length of the bar, the edges of which sections are engaged together to form the grate-bar and the upper section having an air-discharge orifice therein, and means for fastening said sections in place, the bottom section having an orifice for the introduction of a current of air into the grate-bar, the bottom section being formed with an ash-outlet opening and a closure for said opening, the means for holding the sections en-

gaged comprising a tie-bolt engaged with said closure and extending upward into engagement with the upper section of the grate-bar. 35

3. A hollow grate-bar, comprising upper and lower sections each of approximately the length of the grate-bar, said sections having their edges engaged together, and the upper section having an air-discharge opening and 40 the lower section having an air-inlet opening and an ash-outlet opening, a closure for the ash-outlet opening, a tie-rod engaged with the closure and extending upward to the upper section of the grate-bar, whereby to 45 hold the grate-bar sections engaged and to keep the closure in position, and a strengthening-rib located in the lower section and extending transversely from side to side thereof.

4. The combination with a bridge-wall, of 50 a hollow grate-bar, and means for supplying a current of air thereto, said grate-bar having an air-discharge opening in the end adjacent to the bridge-wall and also having a horizontally-disposed shield juxtaposed to said 55 opening directing the air-current horizontally toward and over the bridge-wall.

In testimony whereof I have signed my name to this specification in the presence of two subscribing witnesses.

THEODORE JOSEPH PRITCHARD.
